(57) **CLAIM**

The ornamental design for a nozzle for laser beam machine, as shown and described.

DESCRIPTION

FIG. 1 is a front view of a nozzle for laser beam machine showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof;

FIG. 8 is a cross-section view taken along the line 8-8 in FIG. 1 thereof;

FIG. 9 is an enlarged view of the section outlined "9" in FIG. 5 thereof; and,

FIG. 10 is an enlarged view of the section outlined "10" in FIG. 6 thereof.

The broken lines shown in the drawings illustrate portions of the nozzle for laser beam machine that form no part of the claimed design.
